Letters Patent No. 756, Dated Jan. 22, 1856.

Ante-dated Dec. 31st, 1855.

The schedule referred to in these Letters Patent and making part of the same. —

To all whom it may concern:

Be it known that we Garrettson Smith, Henry Brown, and Joseph A. Read, of the City and County of Philadelphia and State of Pennsylvania, have produced a new and original Cook stove design, denominated the "Premium," and we do hereby declare that the following is a full, clear and exact description of the same, reference being had to the annexed drawing forming part of this specification, in which.

Figure 1. is a side view of the stove. —

Figure 2. is a front view. —

Figure 3. is a back view. —

Figure 4. is a front view of foot. —

Similar letters of reference denote the same part of stove and design. —

The side plates A. each bear an oven door B. and panel C. one of the latter movable and constituting the feed door for wood. On side plate A. and above door B. is the inscription "premium" in raised capitals. Between door B. and panel C. are the openings a. in plate A. This plate is ornamented by a molding b. below door B. and panel C. —

Door B. is raised above the surface of plate A. by a molding c. made up as shown by section x, x, (fig. 2,) the panel of the door bears an ornament in bas-relief made up of a tablet composed of a series of triangular figures d. radially arranged, on which is the central figure f. and sweeping foliage e. and i. the configuration and arrangement being as shown in figure 1. —

The panel C. is raised above the plate A. by a molding h. made

up as shown in section y.y. (fig: 1.) and bears an ornament in bas-relief made up of figures k and l. and foliage m. arranged and configured as set forth in fig: 1. —

The front doors o. are raised above the front plate by a molding c, made up as shown in section x.x. and are each ornamented in bas-relief by figures y. j. and x. arranged and having the configuration shown in figure 2. —

The back plate d. bears a rectangular panel surrounded by molding q. and embellished by an ornament in bas-relief. made up of figures u. and t. and foliage v. and w. arranged and having the configuration shown in figure 3. —

The foot e. is ornamented in bas-relief by foliage s. q. and r. and lozenge figure p. the whole arranged and configured as shown in fig: 4. —

What we claim as our production and desire to secure by Letters Patent, is the design configuration and arrangement of the several ornaments in bas-relief, and moldings on the plates of stove "Premium", as herein described and shown in annexed drawing. —

In testimony whereof we have hereunto signed our names before two subscribing witnesses. End.
